UNITED STATES PATENT OFFICE.

ARTHUR JEFFERSON WYCHERLEY, OF WELLINGTON, NEW ZEALAND.

LOCK.

1,372,584.

Specification of Letters Patent. Patented Mar. 22, 1921.

Application filed October 25, 1920. Serial No. 419,534.

To all whom it may concern:

Be it known that I, ARTHUR JEFFERSON WYCHERLEY, a subject of the King of England, and residing at Wellington, New Zealand, have invented certain new and useful Improvements in Locks, of which the following is a specification.

This invention relates to locks for doors and the like. Heretofore with locks such as of the Yale type when it is desired to enter a locked door, both hands are required, one to turn the door handle and one to unlock the door, necessitating the laying down of a bag or parcel that is being carried. It has also been found desirable that a person within a room should be undisturbed by any one possessing a key opening the door therewith from the outside, and further that a person should be able to use a room without being locked in by himself unless when desired. These objections and requirements are met by this invention which consists in the leading features and combinations and arrangements of parts hereinafter described.

The invention is illustrated in the accompanying drawings in which Figure 1 is an elevation of a lock with its cover plate removed showing the separate and simultaneous locking arrangements, combined in one lock. Fig. 2 is a section taken through 2—2 on Fig. 1. Fig. 3 is an elevation of a lock with its cover plate removed showing method of locking each bolt separately. Fig. 4 is a part end elevation of Fig. 3 and a part sectional elevation taken through 4—4 on Fig. 3. Fig. 5 is a sectional end elevation taken through 5—5 on Fig. 3. Fig. 6 is a perspective view of a trigger. Fig. 7 is a perspective view of a bolt and its several parts. Fig. 8 is a plan of socket attachable to the trigger shown in Fig. 6 and is designed to engage with extension piece of outside key movement. Fig. 9 is a plan of socket attachable to the trigger shown in Fig. 6 and is designed to engage with squared extension of outer handle. Fig. 10 is a part elevation of a lock with its cover plate removed, showing simultaneous locking arrangement. Fig. 11 is a part sectional elevation through 11—11 on Fig. 10. Fig. 12 is an elevation of the inner face of cover plate showing triggers and sockets in position. Fig. 13 is an elevation of inside of part of a door showing lock in position. Fig. 14 is an elevation of outside of

part of a door showing lock in position. Fig. 15 is an end elevation of part of a door showing lock in position.

In these drawings, the casing 1, to which a cover plate 2 is secured by means of a suitable screw, which passes through hole 3 in cover plate 2 and screws into tapped hole 4 in the casing 1, is mounted on the door 5 in the ordinary manner. The casing 1 is provided with two bolts 6 and 7, one of them, preferably the upper one, being operated by the handle 8 and the other or lower one being operated by the key of the Yale or similar type 9. The bolts 6 and 7 are alike in every respect as shown particularly in Fig. 7 and are each provided with a tongue 10 in which are slots 11 and 12. The bolts 6 and 7 are also provided with pins 13, springs 14, bearing plates 15, and thrust plates 16, these latter being free to move upon pins 13. Attached to bottom of casing 1 and to underside of cover plate 2, and in alinement with one another are two pairs of triggers 17, one of which is shown in Fig. 6. The triggers 17 attached to the casing 1, are operated by handles 18 and 18^a which are on the inside of the door 5. The triggers 17 attached to the cover plate 2 as shown in Fig. 12, are provided with sockets 19 and 20, socket 19 as in Fig. 8 having a rectangular shaped slot to receive the extension piece 20 from the key mechanism 9, while socket 20^a has a square shaped slot to receive the squared extension piece of the handle 8.

In moving back either of the bolts 6 or 7 the trigger 17 is partly rotated to bear against bearing plates 15 causing the latter to move back until stopped by stops 22, thus withdrawing the bolt. At the same time springs 14 are compressed between the back of the bolt and compression plates 16 which in turn bear against pins 24. Note:—Bolt 6 is shown in this position in Figs. 1, 2 and 3. When pressure on the trigger is released, the springs 14, automatically return the bolt to the position as shown at bolt 7 in Figs. 1, 2, 3, 5, and 10. Special apparatus is provided in the casing 1 however to enable the bolts 6 and 7 to be secured, or locked in either the withdrawn or extended positions, either independently of each other, or simultaneously with one another. As shown in Fig. 3, locking plates 25 and 25^a, movable vertically between guides 26 and operated independently by knobs 30 and 30^a, see Fig.

13, engage in slots 11 to lock the bolt in the position as shown at bolt 6, Fig. 3, or engage with back face 10^a of tongue 10 to lock the bolt in the position as shown at bolt 7, Fig. 5 3. A spring operated pin 27 engages in V grooves 28 on the side of locking plates 25 and 25^a to prevent the locking plates from dropping out of contact. In Fig. 10 a locking plate 29 is shown, designed to lock both 10 bolts 6 and 7 simultaneously in either the extended or withdrawn positions. Knob 32 operates locking plate 29 between guides 26, spring pins 27 engaging in V grooves 28; locking plate 29 engages either with grooves 15 11 in tongue 10 or with the face 10^a of the tongue 10 according to the position of the bolts 6 and 7 desired by the operator.

In Fig. 1 both independent and simultaneous locking plates are shown, the former 20 25 and 25^a being operated by knobs 30 and 30^a respectively and the latter 29 by knob 32. In this arrangement, locking plate 29 is provided with cranked extension pieces 34 designed to engage in slots 12 on the upper 25 edge of tongue 10 when bolts are withdrawn, or on faces 10^a of tongues 10 when bolts are extended. Locking plate 29 is provided with guides 26, spring operated pin 27 and V grooves 28 as before described.

30 Bolts 6 and 7 when extended engage in a suitable catch 31 secured to jamb 33 of the usual type.

In operation, the bolts 6 and 7 are movable as desired by means of handles or key provided for same, but they may be locked in either the extended or the withdrawn position at the option of the person within the room to which the door 5 gives ingress. Further the bolts 6 and 7 may be locked 35 either independently or simultaneously as hereinafter described. In Fig. 3 is shown a lock in which the bolts 6 and 7 may be locked independently; the bolt 6 being locked when withdrawn by means of the 40 knob 30 being pushed upward by the operator thereby causing the end 11^a of the locking plate 25 to engage in the slot 11 of the tongue 10, the spring pin 27 engaging in V grooves of the locking plate 25 to prevent 45 same from falling out of gear. Bolt 7 is shown locked in the extended position, the knob 30^a, when moved upward causes the face 12^a of the locking plate 25^a to engage with the face 10^a of the tongue 10 spring 50 pin 27 operating as before described. Bolts 55

6 and 7 may each be locked in either of the positions shown in Fig. 3.

In Fig. 10 is shown a lock in which the bolts 6 and 7 are operated or locked simultaneously by means of a knob 32, which when moved upward lifts locking plate 29 causing the faces 12^a of locking plate 29 to engage with the faces 10^a of tongues 10 on both bolts. For the reverse position of bolts 6 and 7 the faces 11^a of the locking plate 29 60 65 engages in slots 11 of both bolts. In each case the spring pin 27 engages in the V groove 28 as before described.

In Fig. 1 is shown a lock fitted with both independent and simultaneous locking arrangements the independent locking arrangement being operated in exactly the same way as that shown in Fig. 3, while for the simultaneous locking arrangement, the locking bar 29 operated by its own knob 32 70 75 is placed into gear by a downward movement the extension pieces 34 engaging either in the slots 12 of the tongues 10 or the faces 10^a of the tongues 10, according to the position in which it is desired to lock the bolts. 80

Having now particularly described and ascertained the nature of my said invention, and in what manner the same is to be performed, I declare that what I claim is:—

1. A door lock including a casing, two latch bolts mounted in the casing, means for operating the bolts from the outside independently of each other and means operable from the inside whereby either bolt may be secured in the open or in the locked position 90 independently of each other, and both can be so secured simultaneously.

2. A door lock including a casing, two latch bolts mounted in the casing, a handle for operating one of the bolts from the outside, a key for operating the other bolt from the outside independently of the handle operated bolt and means operable from the inside whereby either bolt can be secured in the open or in the locked position independently of each other or both may be so secured simultaneously.

3. A lock as claimed in claim 2 wherein the means for operating the bolts from the inside consists of a pair of independent stops 105 and a single common stop.

ARTHUR JEFFERSON WYCHERLEY.
